UNITED STATES PATENT OFFICE.

CONRAD J. NILL, OF ERIE, PENNSYLVANIA, ASSIGNOR TO ERNST R. BEHREND, OF ERIE, PENNSYLVANIA.

PRESS MECHANISM.

1,333,671.

Specification of Letters Patent. Patented Mar. 16, 1920.

Application filed October 11, 1918. Serial No. 237,766.

To all whom it may concern:

Be it known that I, CONRAD J. NILL, a citizen of the United States, residing at Erie, in the county of Erie and State of Pennsylvania, have invented certain new and useful Improvements in Press Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to pressing mechanism, and has for its object the improvement of my pressing mechanism for which Letters Patent No. 1,203,039 were granted October 31, 1916, to Ernst R. Behrend as my assignee, and consists substantially in the improvements in the press-roll driving mechanism hereinafter set forth and described, and illustrated in the accompanying drawings in which:—

Figure 1, is a top or plan view of the central portion of a pressing mechanism embodying my invention.

Fig. 2, is a side view in elevation of the same.

In these drawings A indicates the endless flexible conveyer, A' the frame of the machine, B, B' (shown in dotted lines in Fig. 2) stationary rolls upon which the endless flexible conveyer is supported, and C, C' vertically movable press rolls mounted in the machine frame and adapted to act on the flexible conveyer over the rolls B, B', the rolls B, B' being driven by gear wheels D, D', on the ends of the shaft D², D³, thereof from a pinion E on a central driving shaft F. Upon the driving shaft F there is a sprocket wheel F' from which a sprocket chain F² leads to the left to a source of power (not shown) for driving the machine; and upon the shaft D³ there is a sprocket wheel from which a sprocket chain D⁴ leads to the right and drives a supporting roll (not shown) for operating the flexible conveyer A. The clutch lever G is only shown diagrammatically, these features being set forth and described in the Letters Patent above referred to, all of which features are a part thereof and form no part of this invention other than to coöperate therewith.

In the frame A' midway between the press-rolls C, C', I mount a driving shaft G on one end of which there is a gear wheel H intermeshing with and driven by the gears D, D', and on the opposite end of the shaft G I secure two sprockets I and I', and on the outwardly extending shafts of the press-rolls C, C', I secure sprockets J and J' of equal diameter with the sprockets I and I'; and extending horizontally between the sprockets I and J, and the sprockets I' and J' there are sprocket chains L and L', which communicate motion from the sprockets I and I' to the sprockets J and J', thereby positively driving the rolls C and C'; the proportions of the gear wheel H to the gear wheels D and D', and the sprockets I and I', and J and J' being such that while the rolls B and B' and the rolls C and C' are all rotated at a uniform speed corresponding with the supporting rolls B, B', and the speed of the travel of the endless flexible conveyer A operating between said rolls, the rolls C and C' are capable of a very considerable vertical movement; this is possible because of the sprocket chain L, L' connection, and is a vital and necessary feature of the mechanism to allow accumulations of the wet bark to pass under the press-rolls C and C' without clogging the operation of the machine; which operation of the mechanism is not practicable unless the rolls C and C' are power driven, and so driven by means other than ordinary spur gearing, which would be out of mesh every time an accumulation of wet bark was carried under them by the belt A, and would operate to clog the mechanism and thereby interfere with the successful operation of the machine. This improvement on the patented machine overcomes serious defects in the operation thereof, inasmuch as it prevents the clogging of the wet bark in front of the rolls C and C', and thereby greatly facilitates the successful operation of the machine.

Therefore having described the construction and operation of my improvement so as to enable others to construct and utilize the same what I claim as new and desire to secure by Letters Patent is:—

1. In a continuous press mechanism the combination of a lower horizontal roll mounted in the machine frame, a transverse driving shaft geared to and operating said lower roll, a continuous flexible conveyer

- resting upon said roll and traveling in unison with the rotation thereof, a vertically movable press-roll resting upon said conveyer vertically above the lower horizontal roll and journaled so as to be vertically movable in the machine frame, and a sprocket chain mechanism connecting said driving shaft with said vertically movable press-roll, whereby said press-roll is driven, regardless of its vertical movement, at a uniform speed with the lower roll, and with the travel of the endless conveyer, substantially as set forth.
2. In a continuous press mechanism the combination of a plurality of lower power driven rolls mounted horizontally in the machine frame, an endless flexible conveyer resting upon said rolls and traveling in unison with the rotation thereof, a press roll resting upon said conveyer above each of
- said lower rolls and vertically movable in the machine frame, gear wheels on each of the lower rolls for driving them, a transverse shaft mounted in the frame between the press rolls, a gear wheel on one end thereof intermeshing with and driven by the gear wheels on the lower rolls, sprockets on the opposite end of said shaft, sprockets on the ends of the press roll shafts, and sprocket chains leading from the sprockets on said transverse shaft to the sprockets on the shafts of the press rolls whereby the press rolls are driven at a uniform speed with the lower rolls and with the travel of the endless conveyer, substantially as set forth.
